UNITED STATES PATENT OFFICE

130,061

DESIGN FOR A LACE TABLECLOTH OR SIMILAR ARTICLE

James Waterfield, deceased, late of Philadelphia,
Pa., by Edith B. Waterfield, administratrix,
Philadelphia, Pa., assignor to Quaker Lace
Company, Philadelphia, Pa., a corporation of Pennsylvania

Application July 16, 1941, Serial No. 102,182

Term of patent 3½ years

To all whom it may concern:

Be it known that James Waterfield, formerly a citizen of the United States, residing in Philadelphia, county of Philadelphia, State of Pennsylvania, but now deceased, did during his lifetime invent a new, original, and ornamental Design for a Lace Tablecloth or Similar Article, of which the following is a specification, reference being had to the accompanying drawing forming part thereof in which the figure is a plan view of substantially a quarter section of a lace tablecloth or similar article showing the new design, the other sections being identical with that here disclosed, arranged in proper relation to complete the lace tablecloth. The quarter section is shown in a dark background to bring out the details of the lace design.

What is claimed is:

The ornamental design for a lace tablecloth or similar article, substantially as shown and described.

EDITH B. WATERFIELD.
Administratrix of the Estate of James Waterfield, Deceased.
